[57] CLAIM

The ornamental design for a connector housing, as shown and described.

DESCRIPTION

FIG. 1 is a front elevational view of a connector housing showing our new design,

FIG. 2 is a rear elevational view,

FIG. 3 is a top plan view,

FIG. 4 is a bottom plan view,

FIG. 5 is a right side elevational view, the left side being a mere image thereof; and

FIG. 6 is a sectional view taken from line VI in FIG. 1.
